UNITED STATES PATENT OFFICE.

GEORGE WILKINSON, OF PROVIDENCE, RHODE ISLAND, ASSIGNOR TO THE GORHAM MANUFACTURING COMPANY, OF SAME PLACE.

DESIGN FOR BORDER FOR SILVER AND PLATED WARE.

Specification forming part of Design No. 7,865, dated November 17, 1874; application filed September 21, 1874.
[Term of Patent 7 years.]

CASE A.

To all whom it may concern:

Be it known that I, GEORGE WILKINSON, of the city and county of Providence and State of Rhode Island, have originated a new Design for a Border for the Ornamentation of Silver and Plated Wares, and of wares in other metals, of which the accompanying photograph, with this specification, is a full and complete description, substantially as shown in the said photograph.

I claim—
The design for a border, substantially as herein set forth.

GEORGE WILKINSON.

Witnesses:

J. F. P. LAWTON,
WM. H. CRINS.
